LE VERN FOX, OF ST. LOUIS, MISSOURI.

METHOD OF REPAIRING CUTS IN PAVEMENTS.

Application filed December 27, 1927. Serial No. 242,594.

My invention relates to a method of permanently repairing cuts, or holes in street pavements and more particularly, although not limited thereto, trench cuts made by 5 plumbers, public utility companies, city employees and the like, thereby eliminating the customary temporary repair.

It is well known that street pavements are damaged by trench cuts made therein by 10 plumbers, public utility companies and city employees and that these cuts usually cause a depressed or sunken place in the pavement shortly after the customary temporary repair has been made due to the dirt refill settling in 15 the trench, and that this condition exists in the pavement until the permanent repair has been made by the city. The customary permanent repair is not practical immediately after the trench has been filled with loose dirt 20 due to the dirt fill settling, hence the usual temporary repair is made to allow the dirt fill to settle before a permanent repair is made.

An object of my present invention is to 25 eliminate the usual temporary repair by making the permanent repair immediately after the dirt fill has been made, as settling of the loose dirt fill in the trench cut has no ill effect upon my permanent repair.

Other objects of my present invention are 30 to provide a new and simple method of permanently repairing cuts in pavements, which includes, first, undercutting the lower edge of the permanent concrete base bounding the 35 trench cut; second, cutting away the solid earth directly below the concrete base undercut to the desired depth to provide a solid earth shoulder bounding the trench cut; third, driving suitable supports into the solid 40 earth on one or more sides of the trench cut and leaving their upper ends exposed in an angular position into the trench cut above the dirt fill; fourth, providing the trench cut with a plurality of crossed reinforcing 45 members; fifth, filling wet concrete into the trench cut above the dirt fill approximately to a level with the concrete base of the pavement, which embeds the reinforcing members and the exposed ends of the supports, sixth, 50 laying suitable pavement finishing material upon the concrete base fill; and seventh, when desirable, placing a protecting plate over the finishing material until such time as the concrete fill has become set to avoid damage to 55 the pavement cut repair by traffic moving

over the repaired section of the pavement before the concrete base fill has become set.

A further object of the invention is to provide a simple, quick, inexpensive and highly efficient method of permanently repairing 60 cuts in pavements so that the repaired section of the pavement will be as good as when in its original condition and having such advantages as will appear more fully from the following description.

In order to enable others skilled in the art to which the invention relates to make and use the same, I will now proceed to describe it, referring to the accompanying drawings, 65 in which:

Fig. 1, is a sectional elevation of the usual pavement cut and trench therebelow.

Fig. 2, is a transverse sectional elevation of a pavement cut and trench fill, showing the undercut recess in the original concrete 75 base, the solid earth ledge or shoulder, the repaired concrete base supporting members.

Fig. 3, is a top plan view of a pavement showing a portion of the pavement cut before the concrete base has been filled in place; so a portion after the concrete base has been filled in place; and a portion showing the surface finishing material in position upon the repaired concrete base.

Fig. 4, is a detail showing a modified arrangement of the solid earth ledge for the repaired portion of the concrete base.

Fig. 5, is a transverse sectional elevation of the pavement cut repair when completed.

Fig. 6, is a longitudinal sectional elevation 90 of the pavement cut repair when completed.

Fig. 7, is a perspective view of the pavement cut repair after bricks, or blocks have been positioned as a surface finishing material.

Fig. 8, is a plan view of a modified arrangement of the concrete base fill supporting members.

My invention or discovery is adapted for permanently repairing pavement cuts to 100 eliminate the temporary repairing thereof, and, as illustrated in the drawing, the reference numeral 1 designates a cut in a pavement 2 which passes through the finishing material 3 and the concrete base 4 of the 105 pavement, and, which extends downwardly into the solid earth 5 in the form of a trench 6. The cut in the pavement referred to is the usual cut made by plumbers, gas and electric companies, cities and others in order 110

to dig a trench to be used for the laying of conduits, pipes, etc., therein, and, in the present known methods the trench 6 and cut 1 is temporarily filled, until such time as city 5 employees of the street department can arrange to permanently repair the cut in the pavement in the usual well known manner, which is usually not until long after the temporary repair has been made by those who 10 made the cut, thus allowing a hole or depression to develop in the pavement which becomes an annoyance to traffic as well as an unsightly spot in the pavement. On the other hand, were the usual permanent repair made 15 immediately, or soon after the filling of loose dirt into the trench 6, it would in time pack and settle in the trench below the lower face of the concrete base repair, thus leaving a weak spot in the pavement which will sooner 20 or later naturally settle with the dirt fill due to traffic constantly rolling over the repaired section in the pavement.

In repairing cuts in pavements by means 25 of my method of permanent repair, settling of the dirt fill in the trench will not in any way weaken the concrete fill thereabove and the finishing material laid thereupon so as to allow a depression to be formed in the surface of the pavement due to the dirt fill 30 settling.

In repairing any such pavement cuts, the hole or trench 6 in the solid earth 5 is filled in the usual manner with loose dirt 7 to its original height and should parties engaged 35 to make the permanent repair fail to be on hand at that time, a suitable cover plate 8 is preferably placed over the pavement cut 1 in the pavement 2.

My method of repair begins after the dirt 40 fill 7 has been attended to and it consists in undercutting the end walls 9 and side walls 10, of the original concrete base 4 bounding the cut 1, to provide an undercut endless pocket 11, as clearly shown in Figs. 2, 45 and 5, and further in the cutting away of the solid earth 5 directly below the undercut portions 11 of the concrete base 4 to the desired depth to provide, preferably, an endless solid dirt ledge, or shoulder 12, although 50 not necessarily so, as the base may, without departing from the spirit of the invention be undercut at spaced distances to provide spaced undercut pockets 13 and spaced ledges, or shoulders 14, as shown in Fig. 4, instead 55 of an endless undercut and endless solid dirt ledge, or shoulder 12, as shown in Fig. 3.

After the above has been accomplished, I 60 provide the solid end walls 9 of the trench cut 6 with a plurality of suitable supporting members 15 and the solid side walls 10 of the trench cut 6 with a plurality of like supporting members 16. The members 15 and 16 are driven into the solid earth 5 by any suitable means with a portion of the upper ends 65 of the supporting members 15 and 16 ex-

posed into the trench cut 1 above the dirt fill 7. The supporting members 15 are each driven into the solid earth 5 at an angle to the wall of the trench and can be arranged in parallel relation as shown in Figs. 2, 3 70 and 4, or they may be disposed at an angle to each other, as shown in Fig. 8, with the upper ends arranged closer to one another than the inner, or lower ends thereof. Likewise the supporting members 16 are preferably disposed in parallel arrangement, as 75 shown in Figs. 3 and 6, although not necessarily limited thereto, as they may also be arranged at an angle to each other.

After the supporting members 15 and 16 have been positioned, a plurality of suitable crossed reinforcing members 17 are positioned and suitably supported a suitable distance above the earth fill 7 and then the space above the earth fill 7 and ledge 12 and between the undercut walls of the original concrete base 4 is filled with wet concrete to a level approximately in a plane with the upper plane of the original concrete base 4. This operation provides a repaired concrete base 80 fill section 18 which rests both upon the loose dirt fill 7, the ledge or shoulder 12, or in the pockets 11, if pockets are used, as shown in Fig. 4, and which concrete base fill section 18 is substantially supported by both the solid 85 earth ledge 12 and the supporting members 15 and 16, the upper ends of which members are embedded in the concrete, as clearly shown in Figs. 5 and 6, so that should the loose dirt fill 7 settle after the concrete base section 18 has set, the supporting members 15 and 16 and the solid earth ledge will support the concrete base fill section 18 in a suspended state above the fill and prevent its 90 settling with the dirt fill 7. The supporting 105 members 15 and 16, as well as the crossed members 17 reinforce the concrete base fill 18 and insures it against damage due to traffic rolling over the repaired section of the pavement. The undercut walls of the original 110 concrete base 4, as well as the angularly disposed supporting members prevent lifting movement of the concrete base fill section 18.

After the concrete base fill section 18 has been completed, it is topped off with suitable finishing material, which, if the original finishing, or surface material is asphalt or even cement, stone or blocks, is preferably asphalt bricks 19 which will weld themselves together without the use of a filler, or grout, 115 and which will also form a tight joint with the original finishing material of the pavement 2. If a finishing material, such as cement, vitrified bricks, blocks, or the like, is desired in place of the asphalt bricks 19, 120 it may be used without departing from the spirit of my invention, as is manifest.

Finally, after the pavement repair has been made, and in order to protect it for a period 125 of hours thereafter, or until the concrete base 130

fill section 18 can set, I preferably although not necessarily cover the repaired section in the pavement with a suitable cover plate 20, which is removed when the concrete base fill 5 section 18 has become set.

The finishing material, when in the form of asphalt bricks 19, may, or may not be disposed slightly above the upper plane of the original pavement finishing material, and, 10 they may extend to a point below the upper plane of the original concrete base 4, as shown in Figs. 5 and 6, although I do not limit myself thereto.

The many advantages of the herein described method of repairing cuts in pavement permanently, to eliminate temporary repairs, will readily suggest themselves to those skilled in the art to which it appertains.

From the foregoing description, it is evident that a simple and practical method for permanently repairing cuts in pavements has been disclosed, but it is to be understood that I do not desire to restrict, or limit myself to the very details of the method shown and described, which is merely illustrative, it being obvious that changes, not involving the exercise of invention, may be made without conflicting or departing from the spirit of the invention within the scope of the appended claims.

What I claim is:

1. The method of permanently repairing cuts in pavements over a dirt filled trench to eliminate temporary repairs, which consists in undercutting the pavement bounding the cut in the concrete base thereof, forming a solid earth ledge below the undercut portion of the concrete base at the upper edge of the trench, driving supporting members into the solid earth walls of the trench and allowing the upper ends thereof to extend into the concrete base cut, positioning of reinforcing members above the trench fill, filling of concrete into the undercut concrete base cut 45 and upon the solid earth ledge as well as the trench fill to a level substantial with the plane of the undercut concrete base and then applying a surface material to the concrete base fill and finally applying a protecting cover 50 to the surface material.

2. The method of repairing cuts in pavements comprising undercutting the lower edge of the concrete base of the pavement surrounding the cut, inserting a plurality of members into solid earth below the concrete base with their upper ends exposed into said cut, filling the cut and embedding the exposed ends of said members in concrete above a dirt fill to support the concrete fill from 55 sinking.

3. The method of repairing trench cuts in pavements consisting in driving a plurality of supports into the solid earth bounding the trench and allowing the upper ends of the 60 supports to extend upwardly at an angle into

the cut in the pavement and then filling the cut above the trench fill with concrete embedding the upper ends of the supports therein.

4. The method of repairing trench cuts in pavements consisting in driving a plurality of supports into the solid earth bounding the trench and allowing the upper ends of the supports to extend upwardly at an angle into the cut in the pavement, then filling the cut above the trench fill with concrete embedding 75 the upper ends of the supports therein and finally applying a finishing material to the concrete fill.

5. The method of repairing cuts in pavements comprising beveling the lower edge of 80 the concrete base of the pavement surrounding the cut, cutting away the solid earth below the beveled lower edges of the concrete base to provide a supporting ledge, inserting a plurality of members into the solid earth 85 below the pavement and leaving their upper ends exposed into said cut, positioning reinforcing means in said cut, filling the cut and embedding the exposed ends of the said members and said reinforcing means in concrete 90 above a dirt fill and finally applying self sealing bricks upon said concrete fill to resurface the cut.

6. The method of preparing a pavement 95 cut for a permanent repair, which consists in undercutting at an angle the walls of the concrete base surrounding the cut, driving supporting members into solid earth below the undercut portion of the concrete base of the pavement with the upper ends thereof 100 exposed above the fill, filling the pavement cut with concrete to a level with the surrounding concrete base and embedding the exposed ends of the supporting members therein and finally applying surfacing material in the 105 form of asphalt bricks upon the concrete fill.

7. The method of permanently repairing cuts in pavements to eliminate temporary repairs, which consists in undercutting the concrete base surrounding the cut therein, 110 driving supporting members into the solid earth below the concrete base with the upper ends extending into the concrete base cut, filling the concrete base cut with concrete and embedding the upper ends of the supporting members therein and finally applying 115 surfacing material to said concrete base fill.

8. The method of permanently repairing cuts in pavements over a dirt filled trench to 120 eliminate temporary repairs, which consists in undercutting the concrete base surrounding the cut, the cutting of a solid earth ledge below the undercut in the concrete base at the upper edge of the trench, driving supporting members into the solid earth walls of the trench and allowing the upper ends thereof to extend into the concrete base cut, positioning of reinforcing members above the 125 trench dirt fill, filling of concrete into the 130

undercut concrete base cut and upon the solid earth ledge as well as the trench dirt fill to a level substantial with the plane of the concrete base surrounding the cut and then applying a surfacing material to the concrete base fill.

9. The method of making a permanent trench cut pavement repair, which consists of undercutting the lower edge of the original concrete base surrounding the trench cut, cutting away a part of the solid earth below the undercut portion of the original concrete base, forcing supports into the solid earth bounding the trench cut and exposing the upper ends thereof in the trench cut above a dirt fill in the trench cut, positioning of reinforcing members in the trench cut above the dirt fill, filling wet concrete into the trench cut above the dirt fill and embedding the reinforcing members and the upper ends of the supports therein, and finally laying pavement surfacing means upon the concrete fill, the upper face of which is adapted to conform to the contour of the surface of the original adjacent pavement.

10. A structure for repairing pavement trench cuts which consists of angularly disposed supports driven into the solid earth below the pavement, a poured concrete body suspended by said supports in the cut and surfacing material laid upon said concrete body.

11. The method of permanently repairing cuts in pavements comprising undercutting the faces of the concrete base of the pavement

bounding the cut and filling the cut with wet self hardening paving material.

12. The method of permanently repairing cuts in pavements comprising undercutting the faces of the concrete base of the pavement bounding the cut, filling the cut with wet self hardening paving material and applying a surfacing material to said self hardening paving material.

13. The method of permanently repairing cuts in pavements comprising undercutting the faces of the concrete base of the pavement bounding the cut to provide a solid earth ledge below the undercut portion of the base and filling the cut with wet self hardening paving material.

14. The method of permanently repairing cuts in pavements comprising undercutting the faces of the concrete base of the pavement bounding the cut, positioning reinforcing means in the cut and filling the cut and embedding the reinforcing means in concrete above a dirt fill.

15. The method of permanently repairing cuts in pavements comprising undercutting the faces of the concrete base of the pavement bounding the cut, positioning reinforcing means in the cut, filling the cut and embedding the reinforcing means in concrete above a dirt fill and applying a surfacing material upon said concrete.

In testimony whereof, I have hereunto affixed my signature.

LE VERN FOX.
